WILLIAM C. DOWNWARD, OF WILMINGTON, DELAWARE.

TURBINE-ENGINE.

1,283,699.

Specification of Letters Patent.

Patented Nov. 5, 1918.

Application filed April 13, 1917. Serial No. 161,814.

To all whom it may concern:

Be it known that I, WILLIAM C. DOWNWARD, a citizen of the United States, residing at Wilmington, in the county of New Castle and State of Delaware, have invented certain new and useful Improvements in Turbine-Engines, of which the following is a specification.

This invention relates to steam engines and particularly to a steam engine of the turbine type, the principal object of the invention being to provide an engine with an improved type of rotor mounted upon the engine shaft and fitted with novel impact ribs and cross strips against which the entering steam acts to revolve the rotor within the cylinder or housing.

Another object of the invention is to construct the engine in such manner that the rotor may be operated in either direction desired according to the position in which the control valve is turned, the engine being rendered inoperative when the valve is placed in a neutral position between the two steam passages leading to the engine casing.

Another object of the invention is to provide an engine comprising a minimum number of parts fitted and secured together to prevent leakage, the whole forming a steam engine of the turbine type which will be strong and durable, not liable to easily get out of order and which may be rotated in either direction at the will of the operator.

With these objects in view, together with others which will appear as the description proceeds, the invention resides in the novel formation, combination and arrangement of parts, all as will be described more fully hereinafter, particularly pointed out in the claims, and illustrated in the accompanying drawings, in which:

Figure 1 is a view showing the improved turbine engine in vertical section taken in a plane coincident with the axis of rotation.

Fig. 2 is a view of the improved engine in vertical central section taken at a right angle to Fig. 1.

Fig. 3 is a view of a portion of the rotor as seen from the edge thereof, and

Fig. 4 is a cross sectional view of a portion of the rotor taken on the line 4-4 of Fig. 2.

The improved engine of the present invention is shown mounted in a base 10 provided with end standards 11 and with a cradle 12 intermediate the standards to sup-

port the rotor cylinder or engine casing which will be described more fully hereinafter. Carried by the upper end of each standard 11 is a bearing 15, said bearings 60 being fitted to receive the engine shaft 16 which extends across the space between the standards 11 and is provided intermediate its length with an abutment collar 17, threaded on the shaft as shown, or rigid 65 therewith. A short distance from the collar 17 the shaft is threaded as at 18 to carry a clamping collar or nut 19 for a purpose to be hereinafter brought out.

The engine cylinder or casing comprises 70 two side disks or plates 20 of circular form and a shallow annular band 21 between them to which said disks 20 are secured by means of bolts or other fasteners 22. The engine casing rests upon the cradle 12 and 75 is secured thereto by bolts or other fastening means 23. The side walls or plates 20 of the casing are formed with hollow hubs 24 fitted with central bearings 25 through which the engine shaft 16 passes and it will 80 be further seen that these hubs, made hollow as above stated, constitute chambers 26 to receive the exhaust steam from the rotor which passes from thence out through one or more exhaust pipes 14 projecting downwardly from the peripheries of the hubs 24. Bushings 27 are seated in the hubs 24 to 85 form tight joints around the engine shaft and thus prevent danger of steam leaking from the chambers 26 of the hubs. At the 90 top of the cylinder, the annular member 21 is formed with a shoulder 29 upon which a valve housing 28 is secured by bolts or other fastening means 30, said valve casing being formed with a steam passage 31 leading 95 thereto, the passage being branched in opposite directions, as at 32 and 33, within the casing and communicating with aligned steam passages 34 and 35 that open into the interior of the engine casing or housing at a 100 tangent thereto. A rotary valve 36 extends through the valve housing 28 and intersects the steam passage 31 at its connection with the branch passages 32 and 33, said valve forming with a passage 37 which when in 105 the position shown in Fig. 2, will admit steam at full pressure to one side of the engine and rotate the same in that direction, but when the valve is turned by the handle 38 to the position indicated by dotted lines 110 in said figure, steam will pass to the opposite side of the engine and reverse its rotation,

The rotor of the steam engine is mounted upon and rigidly secured to the engine shaft 16 between the abutment collar 17 and the clamping collar or nut 19 and is made of 5 two circular plates or disks 39 spaced apart as shown and each provided with an inwardly projecting hub 40 which hubs abut and separate the disks. The rotor is secured to the shaft by means of a key 43 fitting in 10 key-ways 41 and 42 in the hubs and the shaft respectively. The plates or disks 39 of the rotor are provided adjacent their hubs with escape ports 44 for the dead or used steam, the escape ports registering with the 15 chambers 26 in the hubs 24 of the casing and increasing in diameter from within outwardly to permit the steam to pass easily from the rotor into the chambers 26 and thence out through the exhaust pipes 14. 20 Bushings 45 are mounted in seats formed in the walls 20 of the cylinder casing adjacent the hubs 24 and are held in engagement with the disks 39 by springs 46, thus providing means for preventing leakage of steam 25 around the rotor. From this construction it will be apparent that a rotor has been provided within a casing and packed therein in such manner as to necessitate forcing the steam to pass between the side plates of the 30 rotor in order to reach the exhaust ports 44. Between the side plates 39 of the rotor at their peripheries are a plurality of transverse ribs or cross bars 48 fixed at their ends to said disks and spaced a short distance apart. These ribs are of triangular 35 cross section, as shown in Fig. 2, and are arranged with their bases outwardly, their apices projecting inwardly toward the axis of rotation and so present to the steam entering through either of the branches 34 or 40 35 an angular surface to receive the impact of the steam and direct it toward the shaft 16. In addition to the transverse ribs 48 each disk 39 carries a plurality of radial ribs 47 45 of triangular cross section as shown clearly in Figs. 3 and 4 and preferably integrally formed with the disks. The ribs 47 on each disk are spaced a short distance apart and have their bases resting upon the disk, the 50 sides of each rib converging to a crest or edge substantially parallel to the face of the disk, and extending partway across the space between the disks, this extension being such that the ribs on one disk overlap those 55 of the opposite, a narrow steam space being left between the ribs as clearly shown in Fig. 4. The faces of the radial ribs are provided with transverse corrugations 49 as shown whereby the steam passing between the ribs 60 will more readily act upon their surfaces and impart the force of the steam to the rotor. The ribs 47 extend from near the hubs 40 of the rotor to within a short distance of the transverse ribs 48 and are arranged 65 in such relation thereto that the entering

steam striking the inclined faces of the transverse ribs 48 will be deflected against the inclined faces of the radial ribs and so act against said ribs to turn the rotor.

Steam entering the inlet port 31 is directed by the valve 36 when the latter is set as in Fig. 2, to the left and passing thence through the branch 32 and its continuation 34, enters tangentially into the engine casing and impinges upon the rotor, striking the transverse ribs 48 and being deflected by them against the ribs 47 imparts its energy to the rotor and causes the latter to revolve. The radial ribs 47 are made narrower as they approach the axis of rotation and so provide greater space between the ribs of the two disks and so allow for the expansion of steam which after escaping beyond the ribs passes outwardly through the ports 44 into the chambers 26 and from thence out through the exhaust pipes 14, the steam being thus caused to act in the most efficient manner upon the rotor and impart its energy of impact thereto.

The engine is simple, as shown in Figs. 1 and 2 and when in place, the valve 36 may be turned to the right or left to permit steam entering in the same direction to the rotor for the purpose of causing it to revolve to the right or left as desired. When, however, the rotation of the engine is to be stopped, the valve will be turned into such position as to close the branch openings 32 and 33 against the entrance of steam and thus cutting off the rotor the latter will cease to be driven.

From the above it will be clear that a turbine engine has been provided which is simple in construction, efficient in operation and at the same time both strong and durable.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

What is claimed is:—

1. A turbine engine comprising a base, a cylinder casing carried by the base and provided with outlet ports and with an inlet port having branches leading therefrom, means for directing the passage of steam through the inlet into one of the branches thereof, an engine shaft rotatably supported by said base and extending through the cylinder casing, and a rotor mounted upon the engine shaft within the cylinder casing and comprising side disks provided with escape ports adjacent the engine shaft, hub members for said disks fitting upon the engine shaft, means for clamping the hub members

of the side disks in tight engagement upon the engine shaft, the disks being held against rotation thereon, ribs extending from the side disks in overlapping and spaced relation, the ribs being substantially triangular in cross section, and tapering from the outer edges of the side disks toward the hubs thereof, transverse corrugations extending from the side faces of the ribs, and cross bars connecting the edge portions of the side disks and positioned in spaced relation to the ribs and substantially triangular in cross section.

5 10 15 20 25 30 35 40 45 50 55 60 65 70 75 80 85 90 95 100

10 bars connecting the edge portions of the side disks and positioned in spaced relation to the ribs and substantially triangular in cross section.

2. A turbine engine comprising a cylinder casing having central steam outlet chambers forming bearings, an engine shaft extending through the cylinder casing to the bearings thereof, the casing being provided with a live steam inlet having valve controlled branches leading therefrom, and a rotor mounted upon the engine shaft within the cylinder and comprising side disks having hubs fitting upon the engine shaft and held against rotation thereon, the side disks being provided with outlet ports adjacent the hubs and communicating with the outlet chambers of the casing, ribs extending from the inner faces of the side disks in spaced and overlapping relation, the ribs being triangular in cross section and tapering toward the hubs and provided with transverse corrugations, and cross bars connecting the edge portions of the side disks in spaced relation to the ribs and substantially triangular in cross section.

3. A turbine engine comprising a casing forming a cylinder chamber provided with steam inlets and outlets, an engine shaft extending through the casing, and a rotor mounted upon the engine shaft within the casing and comprising side plates rigid upon the engine shaft and extending in spaced relation from the shaft, ribs extending from the inner faces of the side disks in spaced and overlapping relation, the ribs being triangular in cross section and provided with transverse corrugations, and cross bars connecting the edge portions of the side disks and positioned in spaced relation to the ribs and being substantially triangular in cross section.

4. A turbine engine comprising a casing forming a cylinder chamber provided with steam inlets and outlets, an engine shaft

extending through the casing, and a rotor mounted upon the engine shaft within the cylinder casing and comprising side disks having outlet ports adjacent the engine shaft, ribs extending from the inner faces of the side disks between the outlet ports and the outer edges of the disks, said ribs being substantially triangular in cross section, and extending in overlapping relation and tapered toward the engine shaft, and cross bars connecting the side disks and substantially triangular in cross section.

5. A turbine engine comprising a casing forming a cylinder having steam inlets and outlets, a rotor rotatable in said cylinder and having side disks extending in spaced relation, ribs extending from the inner faces of the side disks in spaced relation and tapered toward the central portions of the disks, the ribs being substantially triangular in cross section, and cross bars connecting the edge portions of the side disks in spaced relation to the ribs and substantially triangular in cross section.

6. A turbine engine comprising a casing having inlets and outlets, an engine shaft extending through the casing, and a rotor carried by the engine shaft within the casing and comprising side disks extending in spaced relation and having their central portions provided with escape ports, ribs extending from the inner faces of the side disks in overlapping and spaced relation and extending radially of the disks, and cross bars connecting the side disks and extending in spaced relation to the outer end portions of said ribs.

7. A turbine engine including a cylinder casing, and a rotor in said casing comprising a pair of spaced parallel disks, each disk having spaced radial ribs of triangular cross section extending from its inner face, the ribs of said disks alternating with one another and arranged in overlapping relation to form a tortuous passage between the disks, each rib having transverse corrugations on its sides extending through its length.

In testimony whereof I affix my signature in presence of two witnesses.
